[57] **CLAIM**

The ornamental design for a refuse container dolly, as shown and described.

DESCRIPTION

FIG. 1 is a top left perspective view of a refuse container dolly showing my new design;

FIG. 2 is a top plan view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a bottom plan view thereof;

FIG. 8 is a top left front perspective view of the subject invention, shown with the environmental unclaimed features removed;

FIG. 9 is a top plan view of FIG. 8;

FIG. 10 is a left side elevational view of FIG. 8;

FIG. 11 is a right side elevational view of FIG. 8;

FIG. 12 is a front elevational view of FIG. 8;

FIG. 13 is a rear elevational view of FIG. 8; and,

FIG. 14 is a bottom plan view of FIG. 8.

The broken lines are for illustrative purposes only and form no part of the claimed design.
